CANOPY CLAMPING DEVICE FOR OXYGEN TENTS

Robert J. Reading, Darien, Conn., assignor, by
mesne assignments, to O. E. M. Corporation,
East Norwalk, Conn., a corporation of Con-
necticut

Application January 11, 1952, Serial No. 266,013

11 Claims. (Cl. 128—191)

1

As conducive to an understanding of the invention, it is noted that where the oxygen canopy, which is positioned over the bed, has its usual opening encompassing the juxtaposed inlet and outlet of the oxygen tent and is affixed to the wall of the latter by means of a clamping frame secured by screws or nuts and bolts, the clamping of the canopy in position is both laborious and time-consuming and requires the use of special tools such as screw drivers and wrenches.

It is accordingly among the objects of the invention to provide a clamping frame which is relatively simple in construction having but few parts that are not likely to become deranged, which frame may readily be incorporated with the conventional oxygen tent with but slight changes in the construction thereof and which, with but a few simple manipulations, will dependably retain the periphery of an opening in the canopy against the oxygen tent without the use of screws or bolts and without the need of any tools, yet with assurance that a dependable seal will be effected.

According to the invention the clamping frame which is to be positioned over the substantially rectangular inlet and outlet openings of the intake and cooling chambers of the oxygen tent is desirably substantially rectangular generally conforming to the combined dimensions of such inlet and outlet, one of which is usually positioned above the other in an opening in a wall of the oxygen tent. The clamping frame is hingedly mounted, desirably along one edge, so that it may be moved from opened to closed position. Means are provided to retain the clamping frame in juxtaposition to the wall of the oxygen tent when the frame is substantially in closed position so that the periphery of the opening in the oxygen canopy which is positioned between the frame and the rim of the opening in the oxygen tent, may be retained against such rim. Desirably cam means are provided to effect movement of the clamping frame, after it has been thus retained in juxtaposition to the wall of the oxygen tent, toward the latter to press the rim of the frame against the periphery of the canopy to provide a dependable seal, and resilient means are desirably provided to retain the clamping frame in such clamped position.

In the accompanying drawings in which is shown one of various possible embodiments of the several features of the invention,

Fig. 1 is a sectional view of an oxygen tent and canopy illustrating the mode of use of the clamping frame,

Fig. 2 is a fragmentary detail sectional view on a larger scale of the clamping frame,

Fig. 3 is a view similar to Fig. 2 on a greatly enlarged scale showing the locking assembly,

Fig. 4 is a sectional view taken along line 4—4 60 of Fig. 3,

2

Fig. 5 is a view taken along line 5—5 of Fig. 2, Fig. 6 is a fragmentary view showing the reinforced opening in the canopy, and

Fig. 7 is a front view of the clamping frame.

Referring now to the drawings, in Fig. 1 is shown an oxygen tent 11 which may include a refrigerator unit 12 which is connected through suitable conduits to a cooling chamber 13 in the upper portion of the oxygen tent. The cooling chamber 13 may be positioned directly over an intake chamber 14 desirably being separated therefrom by a substantially horizontal partition 15. Desirably an oxygen supply line 16 has its outlet end 17 leading into the intake chamber 14. A suitable suction fan 18 serves to draw the exhaled air from a canopy 19, which may be positioned over a bed 21 on which a patient may be reclining, through the substantially rectangular inlet 22 of the intake chamber 14, which may have a suitable filter 20 associated therewith and such air together with the oxygen is circulated by the fan through the cooling chamber 13 to be discharged through its substantially rectangular outlet 24.

According to the invention, means are desirably provided to facilitate the connection of the canopy 19 to the oxygen tent 11 so that a substantially air tight seal may be effected between such canopy and the inlet 22 and outlet 24 of the intake and cooling chambers which are in communication with the interior of the canopy through a substantially rectangular opening 28 in the rear wall 29 of the oxygen tent.

To this end a canopy clamping member is desirably provided which may comprise a substantially rectangular frame 27 preferably of cast aluminum which is of substantially the same dimensions as rectangular opening 28. As shown in Fig. 2, the frame 27 desirably has a plurality of longitudinal louvres 31 and 32, directed upwardly and downwardly respectively and separated by a longitudinal strip 33 substantially midway between the upper and lower edges 34, 35 of the frame. The strip 33 desirably has a rearwardly extending flange 36 preferably formed integral therewith, the edge 31 of which, when the frame is in locked position, will abut against a resilient strip 38, preferably of rubber, affixed to the edge 39 of partition 15 to provide a seal between the inlet 22 and outlet 24 of the intake chamber 14 and cooling chamber 13.

The frame 27 is pivotally mounted to the rear wall 29 of the oxygen tent so that it may be moved into and out of juxtaposition with the opening 28. To this end a pair of hinges 41 are located respectively, near the side edges 42 of the frame 27. Each hinge comprises a pair of complementary hinge members 43 and 44, the members 43 being affixed respectively as by welding as at 45 near each of the ends of elongated supporting members 46, the latter being af-

fixed as by welding as at 47 to the inner surface of the rear wall of the oxygen tent adjacent the lower edge of the opening 28 therein and desirably extending parallel thereto. Desirably the floor 49 of the intake chamber 14 has a resilient strip 51 at its edge 52 against which the supporting member 46 may abut as at 53 to provide a seal. The hinge member 43 coacts with the complementary hinge member 44 which, as shown in Fig. 2, desirably has a rearwardly extending arm 54 with an upwardly curved extension 55, the latter having a mounting portion 56 at its free end which extends at right angles to arm 54. The mounting portions 56 of the hinge members 44 are affixed respectively as by bolts 57 to the free ends 58 of the depending arms 59 of substantially L-shaped brackets 61, the latter each having an arm 62 extending at right angles to arm 59 and affixed as by screw 63 to the flange 36 near each of the ends thereof respectively.

Encompassing the periphery of the opening 28 and affixed to the outer surface thereof is a resilient strip 65, preferably of rubber, through which extends a plurality of mounting studs 66, the latter desirably being mounted on and spaced along the upper and lower edges of opening 28.

With the construction thus described, the frame 27 may be pivoted on the hinges 41 so that its rim can be moved into and out of juxtaposition with the resilient strip 65, from the position shown in full lines in Fig. 2 to the position shown in broken lines. Desirably the rim of the frame 27 has a plurality of recesses 68 therein to receive an associated stud 66 when the frame is moved to closed position as shown in Fig. 2. Thus, the rim of the frame may be snugly seated against resilient strip 65 to effect a dependable seal.

Means are provided securely to retain the rim of frame 27 against resilient strip 65. To this end, as shown in Figs. 2 and 3, a locking assembly 70 is mounted on frame 27 near the upper edge 34 thereof substantially midway between its side edges 42. The locking assembly desirably comprises a latch member which may be a substantially cylindrical stud 71 having an outstanding annular flange 72 near one end thereof with an axial extension 73 which mounts a substantially rectangular locking head 74. The stud 71 is desirably threaded along its length as at 75 between flange 72 and its end 76 and extends through a bore 77 in a downwardly extending block 78 desirably formed integral with the upper edge 34 of the frame midway between the side edges 42 thereof. Screwed on said stud 71 is a hollow cap 79, which desirably is of reduced outer diameter as at 81 defining a shoulder 82. The reduced portion of cap 79 is rotatable in bore 77, and a coil spring 83 compressed between flange 72 and a shoulder 84 formed by an enlargement 85 of bore 77 normally retains shoulder 82 of cap 79 against the outer periphery 86 of bore 77.

Associated with the locking head 74 is a substantially rectangular locking plate 87 affixed at its upper edge to and depending from a channel member 89 extending longitudinally of the upper edge of opening 28 and affixed to the inner surface of wall 29. Desirably the top wall 91 of cooling chamber 13 has a resilient strip 92 at its outer edge 93 which engages channel member 89 to provide a seal. The plate 87 desirably has a substantially rectangular opening 94 therein which, when the frame 27 is moved to locking position will be substantially aligned with locking head 74. The dimensions of opening 94 are but slightly larger than that of locking head 74

so that when the latter is moved into the opening 94 and rotated in the manner hereinafter to be described, the frame 27 will be locked to the plate. In order to rotate the locking head 74, the yoke end 96 of a handle 97 is so positioned that the legs 98 of the yoke straddle the end of cap 79. By means of a pin 99 which extends through legs 98, cap 79 and through the bifurcated end 101 of stud 71, the handle is securely retained in place.

As shown in Fig. 3, the ends 102 of legs 98 are desirably formed with cam conformations so that upon movement of the handle from the position shown in Fig. 3 to the position shown in Fig. 2, the frame 27 will be cammed inwardly against the tension of coil spring 83. By reason of the tensed coil spring 83 and cam conformations, the handle 97 will securely, yet releasably be retained in such upper position.

To affix the canopy 19 to the oxygen tent 11 with the clamping frame 27 in open position as shown in broken lines in Fig. 2, the substantially rectangular opening 104 in the canopy is stretched over the frame 27 so that the studs 66 will extend through corresponding openings 105 in the reinforced upper and lower edges of the opening 104.

The clamping frame 27 is then pivoted on its hinges 41 toward closed position and the handle 97 is rotated 90 degrees from the position shown in Fig. 3 so that the locking head 74 will be aligned with opening 94 in locking plate 87. The handle is then pressed inwardly so that the locking head will pass through opening 94 and the handle is thereupon rotated 90 degrees to the locked or closed position shown in Fig. 3. By reason of the coil spring 83 which reacts against frame 27, the rim of the latter will be slightly spaced from the periphery of the opening 104 in the canopy so that different thicknesses can be accommodated. To move the rim of the frame into clamping position against such periphery, it is merely necessary to lift the handle to the position shown in Fig. 2. As a result, the cam conformations will move the frame against the resistance of coil spring 83 so that the rim of the frame will press or clamp the reinforced periphery of the canopy tightly against resilient strip 65, to effect a dependable seal.

With the construction thus described, the canopy may be securely yet removably affixed to the oxygen tent without need for the use of any tools to loosen screws or nuts. The camming action effected will move the rim of the clamping frame against the rim of the opening of the canopy to retain the latter against the resilient strip 65 with resultant dependable sealing action.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. An oxygen tent having a wall with an opening therein, a clamping frame, means hingedly mounting said frame on said wall so as to be movable from open position to closed position in juxtaposition to said opening, locking means to

retain said frame in such closed position, a handle to control said locking means, means upon movement of said handle to effect movement of said frame from such closed position to clamping position and means to lock the frame in such clamping position.

2. The combination set forth in claim 1 in which a locking plate is mounted on said wall, said plate having an elongated opening therein, a locking stud rotatably and slidably mounted in a bore in said frame extending at right angles thereto, said stud having an elongated locking head of dimensions slightly smaller than said elongated opening so that when said frame is moved to closed position, said locking head may enter said elongated opening, means to rotate said stud whereby said locking head will engage the periphery of said elongated opening to retain the frame in closed position, cam means coacting with said frame to slide the latter along said stud to move the frame to clamping position and resilient means coacting with said cam means to lock the frame in clamping position.

3. The combination set forth in claim 1 in which a locking plate having an elongated opening therein is mounted on said wall, said frame having a block adapted to be aligned with said locking plate when the frame is in closed position, a stud extending through a bore in said block at right angles thereto, said stud having a flange near its inner end with an axial extension having an elongated locking head at the end thereof of dimension slightly smaller than said elongated opening so that when said frame is moved to closed position, said locking head may enter said elongated opening, a cap affixed on the other end of said stud on the outer side of said frame, said cap having an external shoulder adapted to engage the outer periphery of said bore, a coil spring coacting with said flange and the inner side of said frame normally to urge the locking head inwardly to retain the shoulder of said cap on said periphery and means to rotate said stud whereby the locking head will engage the periphery of said elongated opening.

4. An oxygen tent comprising a wall with a substantially rectangular opening therein, a substantially rectangular clamping frame of dimensions slightly larger than the dimensions of said opening, means hingedly mounting said frame along one edge thereof on said wall so as to be movable from open to closed position in juxtaposition to said opening, means releasably to retain the frame in such closed position, a handle controlling said means, means upon movement of said handle to effect movement of said frame from such closed position to clamping position with the rim of said frame pressed against the periphery of said opening and means to lock the frame in such clamping position.

5. The combination set forth in claim 4 in which said oxygen tent has a substantially rectangular inlet and a substantially rectangular outlet positioned one above the other, said inlet and outlet being in communication with said opening and said frame has a pair of sets of longitudinal louvres thereon directed upwardly and downwardly respectively and associated respectively with said outlet and inlet.

6. The combination set forth in claim 4 in which said oxygen tent has an intake chamber and a cooling chamber with a substantially

horizontal partition therebetween, said chambers having a substantially rectangular inlet and a substantially rectangular outlet associated therewith, positioned one above the other and in communication with said opening, the edge of said partition being between said inlet and outlet adjacent said opening, and said frame having a pair of sets of longitudinal louvres therein directed upwardly and downwardly respectively and associated respectively with said outlet and inlet, said sets of louvres having a longitudinal strip therebetween with a rearwardly extending longitudinal flange, said flange abutting against the edge of said partition to form a seal when the frame is in closed position.

7. The combination set forth in claim 6 in which the edge of said partition has a resilient strip thereon against which said flange abuts.

8. An oxygen tent comprising a wall with a substantially rectangular opening therein, a plurality of mounting studs affixed to the periphery of said opening and extending outwardly from said wall, a clamping frame, means hingedly mounting said frame on said wall so as to be movable from open position to closed position in juxtaposition to said opening, said frame having a rim of dimensions corresponding to those of the periphery of said opening, said rim having recesses therein aligned with said studs when the frame is in closed position, means to retain said frame in such closed position, a handle controlling said means, means upon movement of said handle to effect movement of said frame from such closed position to clamping position and means to lock the frame in such clamping position.

9. The combination set forth in claim 8 in which a resilient strip is affixed to the periphery of said opening and said mounting studs extend through said resilient strip.

10. The combination set forth in claim 8 in which an oxygen canopy is provided having a substantially rectangular opening therein of dimensions such that the periphery of said opening may be passed over said frame, said periphery having a plurality of openings therethrough through which an associated mounting stud can extend, properly to position the periphery of the opening in the canopy with respect to the substantially rectangular opening in said oxygen tent.

11. An oxygen tent having a wall with an opening therein, a clamping frame, means hingedly mounting said frame on said wall so as to be movable from open position to closed position in juxtaposition to said opening, said hinge means comprising a hinge member affixed to the wall of said oxygen tent, a complementary hinge member comprising an arm pivotally connected at one end to said first hinge member and extending inwardly of said wall, a curved extension rising from the other end of said arm, said extension being affixed at its free end to said frame, means to retain said frame in such closed position, a handle controlling said means, means upon movement of said handle to effect movement of said frame from such closed position to clamping position and means to lock the frame in such clamping position.
